(57) **CLAIM**

The ornamental design for an anesthesia infection control barrier sheet with pockets, as shown and described.

DESCRIPTION

FIG. 1 is a front and top perspective view of an anesthesia infection control barrier sheet with pockets, showing our new design;

FIG. 2 is a front plan view thereof;

FIG. 3 is a rear view thereof;

FIG. 4 is a top view thereof; and,

FIG. 5 is a side view thereof, taken from the left of FIG. 2.
